REFRIGERATOR

Charles F. Belshaw, Greenville, Mich.

Application March 2, 1939, Serial No. 259,337

8 Claims. (Cl. 62—31)

The object of my invention is to provide a refrigerator of the water-ice type having various improvements in details of construction, to be hereinafter pointed out, of such character as to conserve the ice supply in such manner as to insure a substantially uniform temperature in the refrigerating chamber; to facilitate charging of the ice chamber either with a single large block of water-ice or with an aggregate of smaller pieces of ice; to render various portions of the apparatus, which require frequent cleaning, to be readily removed from the structure while at the same time insuring against accidental displacement; to protect the ice supply from the sudden rush of warm air when the refrigerator is opened for removal or replacement in the refrigerating chamber of articles; to protect the contents of the refrigerating chamber from the inrush of warm air when the structure is opened for charging of the refrigerant chamber and to conceal the contents of the refrigerating chamber from observation by the "ice man"; and to insure the proper intermittent discharge of the water resulting from the melting of the ice.

25 The accompanying drawings illustrate my invention.

Fig. 1 is a front to rear vertical section of a refrigerator embodying my invention;

Fig. 2 a vertical section at right angles to the plane of Fig. 1;

Fig. 3 a horizontal section on line 3—3 of Fig. 1;

Fig. 4 a section on line 4—4 of Fig. 1;

Fig. 5 a section on line 5—5 of Fig. 1;

35 Fig. 6 a section on line 6—6 of Fig. 1; and

Fig. 7 a section similar to Fig. 1 showing a similar structure except that the main casing is provided with independent doors to afford access respectively to refrigerant chamber and the refrigerating chamber, and a modified drainage line is shown.

In the drawings, 10 indicates the main shell of conventional construction, comprising internal and external metal shells 11 and 12 with an intermediate filling 13 of heat insulating material. In Figs. 1 and 2 the front of this shell is provided with an access opening 15 substantially the full height of the structure bounded by a rabbet 16 at the bottom of which is an annular tubular packing 17. The opening 15 is closed by a door 18 provided with a bounding outwardly extending flange 19 to which is secured a tubular packing 20 adapted to contact packing 17, the two packings 17 and 20 compressing each other,

as indicated in Fig. 1, when the door is in closed position.

In Fig. 7, two openings 15' and 15'' are provided, one to afford access to the refrigerant chamber and the other to afford access to the refrigerating chamber, enclosed by doors 18' and 18'' respectively, said doors being of the same general construction as door 18.

Near the upper end of the interior of the main shell 10 and extending across the rear wall of the 10 interior is a bar 25 engaging across the interior of the shell at the front, and slightly below the plane of bar 25 is a bar 26. Bar 25 is held in place by four screws 27.

Depending from bars 25 and 26, and supported thereby, is a hopper H, an intermediate portion of which is formed by downwardly and inwardly inclined imperforate metal sheets 28 forming a four-sided closed figure in horizontal section. The rear and two side portions 28, at their upper 20 ends, are extended upwardly parallel with the adjacent internal wall of the shell and the upper end of the portion 29 immediately adjacent the rear wall of the shell is provided with an out-turned lip 30 which rests upon bar 25. Two 25 of the screws 27 pass only through bar 25 while the other two, conveniently the end screws (Fig. 2), pass through the portion 29 which carries the lip 30. The front plate 28, at its upper ends, is provided with an outwardly and upwardly inclined lip 31 which rests upon bar 26. The front ends of the side plates 29, 29 extend to about the junction between 28 and 31. Extending downwardly from the lower edge of each part 28, and conveniently integral therewith, is a depending plate 32 parallel to the adjacent wall of the main shell. The front and rear plates 32 are medially notched on their under edges, and located in these notches and extending between the two front and rear plates 32 is an imperforate water shed or teeter plate 33 presenting a ridge 35 to the ice supply for purposes which will appear. The side to side extent of the water shed 33, as is indicated in Fig. 2, is somewhat less than one-third of the internal width of the 45 main shell and connecting each edge of the water shed with the adjacent side plate 32 is a series of laterally separated bars 36 which form two ice obstructing grids, one at each side of the medial vertical front to rear plane of the structure, these grids being slightly downwardly inclined toward said medial plane.

Sleeved within the parts 29 is a three-sided retainer I formed of sheet metal and U-shaped in horizontal section, the rear wall 40 of this 55

structure I lies against the forward face of the rear portion 29 and is perforated to receive the two end screws 27, 27 by which the structure I is held in vertical position. Each side wall of the structure I telescopes within and closely adjacent the side walls 29 of hopper H and each carries near its forward end a depending finger 41 spaced from the side wall of the structure I and adapted to be projected downwardly over the upper edge adjacent side wall 29 with finger 41 outside of said side wall, thus holding the side wall of structure I against lateral displacement, as clearly shown in Fig. 2. The three sections or walls of retainer I form vertical supplements for the back and sides of the ice support.

The forward vertical edge of each side wall 40 of structure I is provided with a laterally spaced and rearwardly projected flange 42 (Fig. 4).

Projecting upwardly from bar 26 is a fulcrum flange 45 upon which is fulcrumed a door 46 which, in its upper normal position, serves to close the space between the forward edges of the side walls of structure I, said door, along its lower edge at its inner face, being provided with a depending flange 47 which, with the lower edge of the door, forms a fulcruming crotch for the reception of the fulcrum flange 45. Door 46, at each side, carries a plate 48 which overlaps the adjacent side wall 40 of structure I. Each of these plates 48, at its lower edge near flange 47, is provided with an inwardly and upwardly turned finger 49 which, in all positions of plate 48, interdigitates with flange 42, the construction and arrangement being such that so long as the side walls 40 of structure I are in normal position, door 46 with its side plates 48 cannot be removed from the structure although it may be freely swung on the horizontal axis formed by the upper edge of the fulcrum flange 45. Sealed to the inner face of each plate 48 is a hook 50, which, by swinging movement of door 46 may be brought to interdigitate with flange 42 and thereby limit the outward swing of door 46. The hook 50 is removably attached to plate 48 by screws 51 and may be placed in various positions of adjustment on plate 48 as indicated by the series of screw receiving holes 52 so that the limit of outward swing of door 46 may be adjustably determined. When large block ice is used, hook 50 is so positioned that door 46 may be swung to a substantially horizontal position, while, if broken ice is to be used, door 46 may be limited in its outward swing to an inclined position which will facilitate the flow of broken ice into the ice chamber without being spilled on the floor.

In order that the ice receptacle may be readily cleansed, the two end screws 27 may be removed, whereupon the forward ends of the side walls 60 of the structure may be lifted so as to withdraw hooks 41 from overlap upon the side walls 29 of the hopper H, whereupon the interdigititation of the lower ends of flanges 42 with the fingers 49 may be destroyed so that door 46 may be readily withdrawn from the structure.

Sleeved around the lower end of hopper H is an air baffle 55, rectangular in horizontal section and extending downwardly from a point slightly above the lower edge of hopper H to a point sufficiently below the grids 36 to afford room for the medially perforated drip pans 57 and 58. These drip pans are provided with medial eyes 57' and 58' respectively, defined by an upwardly extending flange, these eyes being of smaller dimensions laterally front to rear than the ridge

plate 35, said ridge plate, at its side, being formed of comparatively sharp depending ridges 33', 33' which lie beyond the eyes 57' and 58'. The pan 57 is conveniently integral with baffle 55 and the combined structure is removably supported in the shell in any suitable manner as, for instance, by notched fingers 59 carried by the side walls of baffle 55 and resting upon pegs 60 carried by the side walls of the shell 10. The side walls of baffle 55, above pan 57, carry inwardly projecting ledges 61 upon which pan 58 is slidably mounted, the said pan, at its front end, being provided with a notched bar 62 arranged to receive the upper edge of the forward wall 57" of pan 57 when pan 58 is in operative position. The pan 58 is thus readily removable from pan 57 by the slight lifting of its forward edge, whereupon it may be drawn out of the main shell. Pan 58 receives all of the drippage from the ice, whereas pan 57 really receives the condensate from the bottom of pan 58 so that pan 58 requires more frequent cleaning than does pan 57; hence the provision of means for ready withdrawal of pan 58 from its normal association with pan 57.

The front wall 58", which extends between the front ends of the side baffles 55 and which may be integral with pan 57, is extended upwardly somewhat above the top of baffle 55, as clearly shown in Fig. 1, for the reason that the major inflow of warm air occurs when the door 18 is opened, and the upward extension of the wall 58" prevents too great an inflow of warm air to the exposed ice adjacent the opening and equalizes this inflow of warm air around the entire lower end of the ice hopper.

Outflow from pan 58 is through a conduit 64 which discharges into a conduit 65 leading from pan 57. Conduit 65 delivers into a normally fixed conduit 66 arranged within the refrigerating chamber at one side thereof and supported by the readily removable cover 67 of a water-seal tank 68 conveniently of a capacity in the neighborhood of a pint, and discharges through the siphon 69, the inlet end of which lies very close to the bottom of tank 68 and the crown of which, as indicated at 70, is so restricted that the meniscus, at the time the level of water in the tank reaches the lowermost point of the crown, will so nearly fill the passage that another drop arriving through conduit 66 will completely fill the restricted portion of the conduit and thus start the siphoning action. I have found that a tube having an internal diameter of $\frac{1}{8}$ " to $\frac{1}{4}$ " at the crown will generally accomplish this result, so that intermittent siphoning action is insured and that drip leakage over the crown of the siphon is avoided. However, in order to insure absence of drip leakage over the crown of the siphon and to insure adequate intermittent siphoning action, I perforate cover 67 as indicated at 71 so that, when door 18 is closed by the usual rather sudden movement, the increase of air pressure within shell 10 will act on the surface of the water in tank 68 to start the siphoning action.

Arranged within the refrigerating chamber below pan 57 are the shelves 75 preferably of grid construction and each having a rear bar 76 and a depending finger 77. Secured to the rear wall of shell 10 are two perforated strips 78, 78 having spaced perforations adapted to receive the upwardly projected finger 79 and rearwardly projected finger 80 of a bracket 81 having an upstanding pin 82 behind which bar 76 of the shelf 75 may be positioned.

In order that the refrigerating chamber and its contents may be protected against the inflow of warm air when the single door of the structure shown in Figs. 1 and 2 is open for ice charging, and in order to hide the contents of the refrigerating chamber from the ice man, I provide the supplemental doors 90, 90 each of which is hinged at 91 at the vertical inner edge of opening 15, said supplemental doors preferably extending from a point just below the upper edge of bar 26 downwardly to the lower edge of opening 15. Each of these supplemental doors may be conveniently formed of sheet metal. A basket 95 is mounted upon the inner face of each of these doors below the air baffle 85 conveniently by means of depending hooks 96, 96 removably supported from eyes or fingers 97 carried by the inner face of the supplemental door. It will be readily understood that these removable baskets 95 may be optional and that, in their absence, the shelves 75 would be extended toward the front of the shell 10 to afford maximum storage space. I believe, however, that the provision of baskets 95 is the more economical and efficient arrangement because, in a main shell of standard dimensions, the shortened shelves 75 are of such width that all the articles placed thereon may be readily observed, whereas wider shelves render the rearmost articles placed thereon somewhat obscure.

I have found it advisable to project the front wall 58' of pan 58 somewhat above the level of the side walls of the side and rear end wall of pan 57 for the reason that the major inflow of warm air into the structure is, of course, through the front, even when the access doors are closed and by this upward projection of the front wall 58', I have been better able to equalize the effect of the circulating air currents, in the refrigerating chamber, upon the refrigerant, by conduction through the walls of the refrigerant container.

When block water-ice is used as the refrigerant, the block will have horizontal dimensions slightly less than the distances between the walls 40 but greater than the distances between the walls 32 and the first charge will rest at its lower edges upon the inclined walls 28. As melting proceeds, correspondingly inclined surfaces will be formed around the lower end of the ice cake and the descent of the ice cake will be somewhat erratic until the lower end of the cake arrives upon the ridge 35 of the water shed or teeter plate 34. This teeter plate will always be cooler than the walls 28 and 32, because of the downwardly moving air currents through the ice of the drip pan, and I have found in actual practice that, even though the main shell does not set perfectly plumb, the ice block automatically levels itself, in a comparatively short time, with its upper surface substantially level and with its whole weight supported upon the ridge of the teeter plate and without complete annular contact between the ice block and the inclined walls 28 and with no ice contact with the walls 32. Apparently, at all times, there will be ice contact with one or the other of the walls 28 parallel with ridge 35 and apparently, melting of this side of the block takes place more rapidly and, in course of time, the block automatically teeters to the other side and, as melting continues, there is repeated teetering of the block upon ridge 35. While I am not at all sure as to the accurate explanation of this phenomenon, it may be that the more rapid melting of the heavier side of the block is due to the intimate contact of the heavy side of the block

with the metal wall 28, while the opposite lighter side of the block is not in actual contact with the metal.

When sufficient melting has occurred to bring the lower end of the ice block into contact with the bars 36 those bars melt into the ice and fins of ice depend from the ice block between the bars.

The bars 25 and 26 prevent circulation of air from the refrigerating chamber front and rear, upwardly into the refrigerant chamber and, at the sides, the upwardly flowing warm air currents come within the influence of the cooled inclined side walls 28 so that they drop down over the side wall pan 57 and consequently the space in the refrigerant chamber is practically a dead air space.

As a consequence of this construction, so long as there is enough ice in the refrigerant chamber to come up to the highest level of the inclined walls 28, the refrigerating efficiency of the structure remains substantially a constant and as a result, ordinary household use of a refrigerator embodying my invention requires reicing only once in five to eight days, although the refrigerant capacity is no greater than the refrigerators of previously known constructions.

In Fig. 7, I show a modified drainage line. Here the tube 65 discharging from pan 57 discharges into the vertical tube 100 which, near its lower end is bent to form trap 101 discharging at 102 into the upper end of a rubber tube 103 leading to the base of the refrigerator and discharging into a preferably metal tube 104 fixed in the floor. Tube 103, at its upper end, when associated with the lower end 102 of tube 100, fits tightly in the bottom of the refrigeration chamber so as to form an air seal, but otherwise is loose and readily removable. The length of tube 100 above trap 101 is preferably as great as possible within the limits of the refrigerator. Under normal conditions of use the rate of flow of water through trap 101 is not sufficient to fill the trap so as to cause intermittent syphoning. In water-ice refrigerators it has been the general practice to provide, in the drainage line, a trap—open to the atmosphere—to prevent entry of air, and such traps must be intermittently cleaned of sediment in order to prevent overflow of water onto the floor of the refrigeration chamber.

In my present construction, the trap 101 is not open to atmosphere within the refrigeration chamber and the height of tube 100 above the trap is such that, if and when the accumulation of sediment in the trap is sufficient to prevent outflow, a sufficient head of water may accumulate in the upper end of tube 100 to overcome the resistance of the sediment and to cause a filling of the peak 105 of the trap, whereupon the syphonic action which is set up will serve to scour the sediment from the trap.

I claim as my invention:

1. A refrigerator, comprising a main shell divided into a refrigerant chamber and a refrigerating chamber by a partially open-bottomed hopper-like structure, comprising, intermediate its height, inwardly and downwardly inclined imperforate walls forming a closed figure in horizontal plane and freely swept externally by air currents, and a ridged heat-transmitting teeter board extended across the mouth of the hopper having substantial transverse extent and its entire under transverse surface freely swept by air currents.

2. In a refrigerator, a two-part drip pan, comprising a bottom pan having upstanding peripheral walls with the front wall shorter, a medial

air-circulation perforation in its floor bounded by an upstanding flange, and a drainage perforation in its floor, and means by which it may be detachably positioned in a refrigerator; and a 5 top pan slidably mounted in the bottom pan over the top of the short wall thereof, said top pan having upstanding peripheral walls, a medial air-circulation perforation in its floor bounded by an upstanding flange, and a drainage perforation 10 in its floor registering with the drainage perforation of the bottom pan, and downwardly-presented notched means horizontally interlockable with a portion of the bottom pan when the top pan is in operative position, whereby, by slight 15 upward lift of the front end of the top pan it may be freed for sliding removal from the bottom pan.

3. In a refrigerator, a two-part drip pan, comprising a bottom pan having upstanding peripheral walls with the front wall shorter, a medial 20 air-circulation perforation in its floor bounded by an upstanding flange, and a drainage perforation in its floor, and means by which it may be detachably positioned in a refrigerator; and a top pan slidably mounted in the bottom pan over 25 the top of the short wall thereof, said top pan having upstanding peripheral walls with the front wall taller than the opposite end wall of the bottom pan, a medial air-circulation perforation in its floor bounded by an upstanding flange, 30 and a drainage perforation in its floor registering with the drainage perforation of the bottom pan, and downwardly-presented notched means horizontally interlockable with a portion of the bottom pan when the top pan is in operative 35 position, whereby, by slight upward lift of the front end of the top pan it may be freed for sliding removal from the bottom pan.

4. In a refrigerator the combination of the main shell and closure therefor, water-ice holding 40 means and water drainage means including a small-capacity tank within the shell with its water content subject to variations of air pressure due to opening and closing of said closure, and a siphon eduction pipe forming the outlet of said 45 tank, said eduction pipe having a cross-section at its peak such that when the water level in the tank approximates discharge level increase of air pressure on the tank content due to closing of the closure insures syphonage.

5. In a refrigerator, the combination with the main shell, comprising a closure, at its front, of 50 ice-supporting means mounted in the shell intermediate its height, vertical removable supplements for the back and sides of said ice support, 55 means for normally holding said supplements in place, a horizontal ridge extending across the fronts of the side supplements in the region of the lower corners and inside and independent of the closure, a door with its lower edge resting on 60 said ridge and a depending lip overlapping the inner face of said ridge, and overlapping elements carried respectively by said door and the side supplements preventing removal of the door but permitting swing of the door on the ridge.

6. In a refrigerator, the combination with the main shell comprising a closure at its front, of 65 ice-supporting means mounted in the shell intermediate its height, a U-shaped flexible vertical supplement for the back and sides of said ice sup-

port, means for normally holding the lower corners of the free ends of said U-shaped member anchored in place, a horizontal ridge extending across the mouth of the U in the region of the anchored corners, a door with its lower edge resting on said ridge and a depending lip overlapping the inner face of the ridge, and overlapping elements carried respectively by the door and the anchored corners of the U preventing removal of the door but permitting swing of the door on 10 the ridge.

7. In a refrigerator, the combination with the main shell comprising a closure at its front and an ice support intermediate its height comprising inwardly converging walls and walls depending therefrom, a two-part drip-pan and air baffle structure mounted in the shell below the ice support, the bottom pan having upstanding peripheral side walls and a rear end wall extending above the lower edges of the depending walls of the ice support, the bottom pan also having a short upstanding front wall, a medial air-circulation perforation with an upstanding bounding flange, a drainage perforation and means for sliding support of a top pan; the top pan slidably nested within the bottom pan and having upstanding peripheral walls with the front wall extending above the lower edge of the adjacent depending wall of the ice support, the top pan also having a medial air-circulation perforation bounded by 20 an upstanding flange, a drainage perforation registering with the drainage perforation of the bottom pan, and a downwardly-presented notched means horizontally interlockable with a portion of the bottom pan when the top pan is in operative 30 position, whereby, by slight upward lift of the front end of the top pan it may be freed for sliding removal from the bottom pan when the closure is opened.

8. In a refrigerator, the combination with the main shell comprising a closure at its front and an ice support intermediate its height comprising inwardly converging walls and walls depending therefrom, a two-part drip-pan and air baffle structure mounted in the shell below the ice support, the bottom pan having upstanding peripheral side walls and a rear end wall extending above the lower edges of the depending walls of the ice support, the bottom pan also having a short upstanding front wall, a medial air-circulation perforation with an upstanding bounding flange, 40 a drainage perforation and means for sliding support of a top pan; the top pan slidably nested within the bottom pan and having upstanding peripheral walls with the front wall extending above the lower edge of the adjacent depending wall of the ice support and higher than the rear wall of the bottom pan, the top pan also having a medial air-circulation perforation bounded by 45 an upstanding flange, a drainage perforation registering with the drainage perforation of the bottom pan, and a downwardly-presented notched means horizontally interlockable with a portion of the bottom pan when the top pan is in operative 55 position, whereby, by slight upward lift of the front end of the top pan it may be freed for sliding removal from the bottom pan when the closure is opened.

CHARLES F. BELSHAW.
